LINGERIE CHEST OR SIMILAR ARTICLE

Huey T. Keller, High Point, N.C., assignor to Gillespie
Furniture Company, Los Angeles, Calif.

Filed Dec. 15, 1972, Ser. No. 315,596

Term of patent 14 years

Int. Cl. D6—04

U.S. Cl. D6—154

FIG.1

FIG. 3

FIG. 1 is a front elevational view of a lingerie chest or similar article showing my new design;

FIG. 2 is a side elevational view thereof, the opposite side being substantially a mirror image of that shown; and

FIG. 3 is a top plan view of such design.

I claim:

The ornamental design for a lingerie chest or similar article, as shown and described.
